UNITED STATES PATENT OFFICE.

JOSEPH H. RODGERS, OF PITTSBURGH, PENNSYLVANIA.

METHOD OF FORMING SAND FROM GRAVEL.

1,401,445.

Specification of Letters Patent. Patented Dec. 27, 1921.

Application filed July 21, 1921. Serial No. 486,477.

To all whom it may concern:

Be it known that I, JOSEPH H. RODGERS, a citizen of the United States, and resident of Pittsburgh, in the county of Allegheny and State of Pennsylvania, have invented a new and useful Improvement in Methods of Forming Sand from Gravel, and I do hereby declare the following to be a full, clear, and exact description thereof.

10 My invention relates to a method of forming sand from gravel, *i. e.*, "the rolled or water-worn material formed from fragments of rock under the combined influence of atmospheric agencies and currents of 15 water" (*Century Dictionary*).

The object of my invention is to provide a method to reduce gravel to the form of sand by means of which the hard gravel which it has hitherto been considered commercially impracticable to crush or reduce to sand may by proper treatment be rendered capable of being reduced to the form of sand in an economic and commercial manner.

25 To this end my invention comprises, generally stated, the method of reducing gravel to the form of sand consisting of heating the gravel and then crushing or grinding the gravel until reduced to the form of 30 sand.

In the accompanying drawing I have illustrated an apparatus for carrying out my invention.

In the drawing the numeral 2 designates 35 a suitable concrete or other foundation upon which is erected a furnace 3 with a heating chamber 4; grate-bars 5; fuel-door 6 and ash-door 7.

40 Mounted above furnace 3 is the cylindrical chamber 8 with the flue 9 leading therefrom. Within the chamber 8 is a cylindrical receptacle 10 which is carried by the central shaft 11 journaled in suitable bearings 12. At one end of the shaft is the 45 bevel-gear 13 meshing with the bevel-pinion 14 on the shaft 15 which may be driven by any suitable power. In this manner rotary movement is imparted to the cylindrical receptacle 10.

50 A chute 16 is provided for delivering the gravel to the receptacle 10.

The receptacle 10 is slightly inclined, and at its outer end is the hopper 17. Arranged in the hopper 17 is the water discharge pipe 55 18 by means of which cold water is discharged into the hopper.

Mounted in housings 19 are the pairs of rolls 20, 21 and 22. The upper pairs of rolls 20 and 21 are corrugated or roughened while the rollers 22 are smooth faced. 60

Adjusting screws 23 are provided for varying the space between the several pairs of rollers.

The gravel contained within the receptacle 10 is heated up to a suitable temperature, and as the receptacle 10 revolves the gravel works its way toward the discharge end and is delivered into the hopper 17. After heating the gravel it is chilled and cooled by the water from the supply-pipe 18. The gravel then passes down, first, through the rolls 20 reducing the gravel to a certain size, then the gravel passes through the rolls 21 which reduce it still further, whereupon it finally passes 75 through the rolls 22 which reduce it to the form of sand. If desired the gravel may be reduced to powdered form, or any degree of fineness.

The heating of the gravel in the above 80 manner renders the same more frangible, and makes it more easily crushed so that the strain and wear on the rolls is greatly relieved, and the gravel can be reduced in an economic and commercial way into the 85 form of sand.

While I prefer to chill the gravel by subjecting it to a cooling liquid as water, before passing it through the rolls yet I do not wish to limit my invention to this chilling 90 or cooling as this step may be omitted and the heated gravel delivered directly to the rolls.

In the appended claims the operations of heating the gravel and crushing the 95 gravel are to be understood as being limited as to the intensity of the heat and the degree of crushing to the production of a final product of the consistency of sand, as distinguished from the heat treatment of 100 ore for the production of fine impalpable powders, and liberation of the minerals contained therein.

By my invention I make available for commercial use in the form of sand, great 105 deposits of gravel as above defined both in river beds and in banks, thereby greatly increasing the production of sand for all kinds of commercial uses.

What I claim is:

1. A method of forming sand from gravel as above defined consisting in heating the 110

gravel, and then subjecting it to a crushing action.

2. A method of forming sand from gravel as above defined consisting in heating the gravel, chilling same, and subjecting it to a crushing action.

3. A method of forming sand from gravel as above defined consisting in heating the

gravel, chilling same by water, and then subjecting said gravel to a crushing action. 10

In testimony whereof, I, the said JOSEPH H. RODGERS, have hereunto set my hand.

JOSEPH H. RODGERS.

Witnesses:

JOHN F. WILL,
H. M. HALL.
